Attorney

UNITED STATES PATENT OFFICE.

LLOYD DELNO GREENLAND, OF DES MOINES, IOWA.

FILE ATTACHMENT.

Application filed June 25, 1924. Serial No. 722,349.

To all whom it may concern:

Be it known that I, LLOYD DELNO GREENLAND, a citizen of the United States, residing at Des Moines, in the county of Polk and State of Iowa, have invented certain new and useful Improvements in File Attachments, of which the following is a specification.

This invention relates to new and useful improvements in attachment for files and has for its principal object to provide a cover for one side of the file whereby the person using the same may readily and easily hold the file without coming in contact with the cutting edges thereof.

A further object of the invention is to provide a file attachment of the above mentioned character, wherein the cover is provided with means for engagement with the forward end of the file, a handle being associated with the opposite end of the cover for engagement with the shank portion of the rear end of the file whereby the cover is maintained in proper position thereon.

A still further object of the invention is to provide a file attachment of the above mentioned character, wherein means is provided for permitting the cover and handle to be readily and easily secured in position on the file, the same being of such a construction as to accommodate various sizes of files.

A still further object of the invention is to provide an attachment of the above mentioned character, which is simple in construction, inexpensive, strong and durable and furthermore adapted for the purposes for which it is designated.

Other objects and advantages of this invention will become apparent from the course of the following description.

In the accompanying drawing forming a part of this specification and in which like numerals designate like parts throughout the same:

Figure 1 is a top plan view of a file with my improved attachment in position thereon.

Figure 2 is a side elevation thereof.

Figure 3 is a sectional view taken approximately on line 3—3 of Figure 2, and

Figure 4 is a top plan view of the blank from which the cover and socket member is constructed.

In the drawing wherein for the purpose of illustration is shown the preferred embodiment of my invention, the numeral 1 designates a file which may be of any conventional construction and the same is provided with the usual cutting surfaces on its opposite sides, the file in the present instance being of the flat type. The rear end of the file is provided with the usual shank portion 2, the purpose thereof being to provide a means for receiving a handle 65 in the manner well known in the art. Ordinarily with the files now in use, a wooden handle is secured in position on the shank portion of the file by driving the tapered point of the shank into the handle. 70

In the present invention, I have provided an attachment wherein a cover for the upper surface of the file is provided and furthermore includes a means for supporting the same in position on the file as well 75 as supporting a handle on the shank portion of the file wherein the person using the same will not come in contact with the cutting surfaces thereof. The attachment comprises an elongated strip of metal 3 80

which is of substantially the same length as the file and the forward end of the strip is disposed downwardly and thence inwardly to provide a hook 4 for engagement with the forward end of the file in the manner clearly illustrated in Figures 1 and 2. The portion of the strip which extends over 85

the upper surface of the file is designated as the cover. Stamped from the blank of metal from which the strip 3 is formed and being integral with the rear portion of the strip is the socket member designated generally by the numeral 5 and the same comprises the coacting sections 6 and 7 90 respectively. The sections taper gradually toward the rear end of the strip 3 and are slit longitudinally as at 8, the purpose of which will hereinafter be more fully de- 95

scribed. Formed on the forward end of the section 7 is the extension 9. Projections such as are illustrated at 10 and 11 respectively in the drawing are also arranged on the forward portion of the section 7 adjacent the extension 9 in the manner clearly illustrated in Figure 4.

When the section 7 is brought into position over the section 6 and the same are bent into the desired shape so that the socket member 5 is provided, the extension 9 will be disposed directly below the rear portion of the strip 3 and the projections 10 and 11 will be bent laterally so as to extend at diametrically opposite points on the forward portion of the socket member 5 in the manner clearly illustrated in Figures 1 and 3 of the drawing. The purpose of the laterally extending projections 10 and 11 will hereinafter be more fully described. The slots 8 in the socket portion 5 serve to provide a plurality of resilient fingers adapted through their resiliency to contact with the shank portion of the file seated therein, and to firmly hold the same, as well as permit of the insertion of shanks and files of varying sizes within predetermined limits.

Cooperating with the socket member 5 and providing a handle for the file is the member 12 and the same comprises a plurality of convolutions of wire, the same tapering gradually from the center of the handle toward the end thereof in the manner clearly illustrated in Figures 1 and 2. The forward end of the handle 12 extends over the forward portion of the socket member and is adapted to be loosely supported thereon so that the convolutions of wire 13 which comprise the handle may cooperate with the laterally projecting members 10 and 11 for securing a binding action of the socket member on the shank portion of the file.

In use, the projections 10 and 11 on the forward portion of the socket member are disposed in the foremost convolution of the wire handle 12 so as to facilitate the insertion of the shank portion 2 of the file in the socket member, it being understood that the forward end of the file is disposed in engagement with the hook 4 on the forward end of the cover or strip 3. After the file has been inserted in proper position, the handle 12 is then turned so as to cause the projections 10 and 11 to travel in the convolutions 13 whereby a binding action on the split socket member 5 will be obtained to cause a further binding action of the socket member on the shank portion of the file, whereby the latter will be securely held in position in the socket member and prevent the displacement of the attachment therefrom.

The provision of an attachment of the

above mentioned character, enables a person using the file to place one hand on the cover which extends over the upper surface of the file while the other hand is employed in holding the handle and the cover will prevent the person from having his hand come in contact with the upper cutting surface of the file when bearing down upon the same during its use. When one of the cutting surfaces has become worn, the attachment may be readily removed from the file and reversed so that the cover will extend over the worn surface of the file and enable the opposite side to be used. The simplicity of my device enables the same to be readily and easily adjusted in position on a file and may furthermore be used in connection with files of various sizes. A device of the character above described will not only be efficient and positive in its operation in securing the attachment in position on a file but will also be inexpensive as well as strong and durable.

While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. An attachment for files comprising an elongated strip of metal extending over the upper surface of the file, a hook formed on the forward end thereof for engagement with the forward end of the file, a socket member on the rear end of the strip receiving the shank portion of the rear end of the file, and a handle extending over the socket member.

2. An attachment for files comprising an elongated strip of metal extending over the upper surface of the file, a hook formed on the forward end thereof for engagement with the forward end of the file, a socket member on the rear end of the strip receiving the shank portion of the rear end of the file, a handle extending over the socket member, said socket member being slit longitudinally, lateral projections at diametrically opposite points on the forward portion of the socket member, and having means for causing a binding action on the socket member when the handle is turned, whereby the file is secured in the socket member against accidental disengagement therefrom.

3. An attachment for files comprising an elongated strip of metal extending over the upper surface of the file, a hook formed on the forward end thereof for engagement with the forward end of the file, a socket member on the rear end of the strip receiving the shank portion of the rear end of the file.

file, a handle extending over the socket member, said socket member being slit longitudinally, lateral projections at diametrically opposite points on the forward portion of the socket member, said handle comprising a series of convolutions of wire gradually tapering from the center toward the ends thereof, said projections cooperating with

the convolutions for causing a binding action on the socket member when the handle 10 is turned whereby the shank portion of the file is secured in the socket member against accidental displacement therefrom.

In testimony whereof I affix my signature.

LLOYD DELNO GREENLAND.
